DRAWBAR FOR HARROWS AND THE LIKE

Gordon A. Irwin, Gwinner, N. Dak., assignor to Melroe
Manufacturing Company, Gwinner, N. Dak., a corpo-
ration of North Dakota

Filed Apr. 1, 1963, Ser. No. 74,228

Term of patent 14 years

(Cl. D39—1)

FIGURE 1 is a side elevational view showing the drawbar for harrows and the like embodying my new design;

FIGURE 2 is a front elevational view thereof;

FIGURE 3 is a top plan view thereof, and

FIGURE 4 is a rear elevational view thereof.

The dominant features of my design reside in the portions shown in full lines.

I claim:

The ornamental design for a drawbar for harrows and the like, as shown and described.
